ATTORNEY.

UNITED STATES PATENT OFFICE.

DE WANE B. SMITH, OF DEERFIELD, NEW YORK.

DESIGN FOR A SPRAYER-BODY.

SPECIFICATION forming part of Design No. 29,973, dated January 10, 1899.

Application filed December 14, 1898. Serial No. 699,273. Term of patent 7 years.

To all whom it may concern:

Be it known that I, DE WANE B. SMITH, a citizen of the United States, residing at Deerfield, in the county of Oneida and State of New York, have invented and produced a new and original Design for a Sprayer-Body, of which the following is a specification, reference being had to the accompanying drawings, forming a part thereof.

Figure 1 shows a perspective view of my present design of sprayer-body. Fig. 2 shows an end view of the same.

The leading or material feature of my design consists of the form and shape of the sprayer-body as a whole and the relative arrangement of the parts, as shown, being the

cylindrical portion 1, with the inlet-head 1^a, and the enlarged dependent cylindrical portion 2, arranged at and immediately beneath one end of the portion 1, as shown.

Having described my invention, what I claim as new, and desire to secure by Letters Patent, is—

The design for a sprayer-body as herein shown and described.

In witness whereof I have hereunto set my hand, in the presence of two witnesses, this 10th day of December, 1898.

DE WANE B. SMITH.

Witnesses:

E. WILLARD JONES,
SARAH A. BROWN.
